J. A. MORIN

CARROTING MACHINE

Filed May 22, 1923

UNITED STATES PATENT OFFICE.

JOSEPH A. MORIN, OF NEWARK, NEW JERSEY.

CARROTTING MACHINE.

Application filed May 23, 1923. Serial No. 640,693.

To all whom it may concern:

Be it known that I, JOSEPH A. MORIN, a citizen of the United States, and a resident of Newark, county of Essex, and State of New Jersey, have invented certain new and useful Improvements in Carrotting Machines, of which the following is a specification.

This invention relates to an improved carrotting machine which is designed to treat fur on skins, so that the proper amount of chemical is supplied to the skin in the carrotting operation so that the fur is slicked down for its entire surface.

In the carrotting of fur the skins at present are laid on a table, and a workman dips a stiff flat brush in a chemical with which the fur is treated, usually nitrate of mercury, and brushes the skin with a few movements of the brush against and with the direction of the fur, slicking it down with the last sweep or two of the brush and piling the skins so treated before they are baked.

The defect in this method is that unless extreme care is used, which care is a rare quality in workmen of the type used in carrotting, all of the fur is not treated, and second, the amount of chemical applied is not easily gaged, since too much chemical will burn the fur, and insufficient chemical will harden the fur and will not give it the proper felting qualities.

The present invention is designed to provide a machine that assures the treatment of the entire skin, and is easily regulated so that the workmen attending the machine apply the proper amount of chemical to the skin, judging the amount by the size of the skin which is inserted in the machine.

The invention is illustrated in the accompanying drawing, in which I show a machine embodying my invention, Figure 1 being a section through the machine. Figure 2 is a side view of the machine, showing a gear connection between the various shafts. Figure 3 is a face view of the brush and its associated rollers. Figure 4 is an enlarged sectional detail, showing a skin passing through the machine, and Figure 5 is a perspective of a part of the means for feeding chemical from the tank to the brush.

The machine comprises any suitable form of standard, and I show one consisting of the legs 10 which are long enough to support the table 11 at the top, about waist-high of a workman or at a slightly higher elevation,

the frame 11 supporting the brush 12 which, in the form shown, is mounted on a shaft 13 and is driven by suitable means, such as the pulley 14 and the belt 15.

Means for supplying chemical, such as nitrate of mercury, is provided, and I show in the drawing a tank 16 which is disposed so that the liquid 17 in the tank is below the brush 12, so that the brush does not come in contact with the liquid, and the supply of liquid is therefore controlled. For this purpose I show a supply roller 18 which is mounted so that it is normally suspended in the liquid 17 and is normally idle, but when moved to contact with the brush 12 it is rotated by the brush, the supply roller being freely revoluble, and it thus picks up enough liquid on its circumference to feed the brush. The roller 18 is usually of wood, which is used on account of its light weight.

In the drawing the means for suspending the supply roller consists of a pair of links 19 pivoted at their top ends, as at 20, to the side of the machine, and having a handle 21. When the handle 21 is pushed in, the supply roller is pressed against the brush, and since the brush is constantly rotating, the roller picks up enough liquid to supply the brush with the proper quantity.

If it is desired to hold the roller in any desired position, such as, for instance, against the brush, a suitable holding means can be provided, such as the pin 22, over which any of the perforations 23 in the handle 21 can be placed.

To feed the skin to the brush I mount a pair of feed rollers 24 and 25, mounted on their respective shafts 26 and 27 and having meshed gears 28 and 29. One of these shafts is positively driven preferably from the shaft 13, and I illustrate the shaft 27 as being driven through the gears 30 and 31 from the gear 32 on the shaft 13. The gearing is proportioned so that the feeding of the skin 33 through the rollers 100 is at a speed slow enough to have the brush 12 give a wiping or slicking action on that part of the skin that is passing over the roller 24, the roller being relatively small and thus bending the skin enough to spread the fur as it contacts with the brush, and then the brush wipes or slicks the fur in the direction of its natural lie, and the skin, passing through not too rapidly, permits all of its length to be thus treated.

110

and since the brush and the feed rollers are wider than the average skin, the skin is treated for its whole width.

The skin has a tendency to wrap itself around the roller 24, and as it rides up it is brushed from the roller by a fending brush 34 which rotates in a direction opposite to that of the roller 24, and in the illustration I show the shaft 35 of the fending brush 34 connected by the gears 36 and 37 with the shaft 27. As the major portion of the skin emerges and passes upward from the roller 24 it falls over and is received on a suitable means, such as the conveyor belt 38 which is usually of rubber or heavy fabric and is mounted on the pulleys 39 and 40, the pulley 40 being driven by suitable means, such as the belt 41 passing over pulleys 42 and over a pulley 43 on the shaft 13.

When the workman is using this machine, if it is a small skin he feeds it between the constantly rotating feed rollers 24 and 25, and pushes the handle 21 in and holds it until the skin has been gripped by the feed rollers, and when the skin is once gripped and is started on its way there has usually been enough chemical supplied to the brush 12 to treat the skin. In the case of a larger skin, of course, the handle 21 is pushed in for a longer period of time. A workman soon becomes accustomed, when he feeds the skin with one hand, to push in the handle 21 with the other and gage the length of time that the supply roller 18 should be in contact with the brush 12, according to the size of the skin that he is treating.

In this machine there is an economy in

the chemical employed, in that it is only applied to the brush and to the skin, in contrast to the present method where it is applied by hand with a flat brush on a flat table, and the whole table becomes wet and there is a waste of chemical.

I claim:

1. A carotyping machine comprising a brush moving in one direction, a means for feeding a skin so that the fur is curved and spread when presented to the brush and at a slower speed than the speed of the brush, a tank for holding liquid, a supply roller in the liquid, and means for moving the roller to contact with the brush.

2. A carotyping machine comprising a brush moving in one direction, a means for feeding a skin so that the fur is presented to the brush and at a slower speed than the speed of the brush, a tank for holding liquid, a supply roller, links for suspending the supply roller in the liquid, and a handle for swinging the links so that the supply roller is moved to contact with the brush.

3. A carotyping machine comprising a rotary brush, a tank under the brush, a supply roller mounted so as to be in contact with liquid in the tank and to be moved in contact with the brush, a handle for moving the brush, and feed rollers closely adjacent to each other and adapted to feed a skin to the brush and to present the furry side of the skin to the brush at a slower speed than that of the brush.

In testimony that I claim the foregoing, I have hereto set my hand, this 21st day of May, 1923.

JOSEPH A. MORIN.
